(57) **CLAIM**

The ornamental design for an earphone holder, as shown and described.

DESCRIPTION

FIG. 1 is a perspective view of front, top and left side of an earphone holder showing my new design;

FIG. 2 is a perspective view of rear, bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a reference view 1 of usage thereof;

FIG. 10 is a reference view 2 of usage thereof; and,

FIG. 11 is a reference view 3 of usage thereof.

The portions of the article in broken lines are shown for illustrative purposes only and form no part of the claimed design.

1 Claim, 9 Drawing Sheets
